SMOKING STAND

James C. Williamson, Albany, Ga.

Application August 15, 1950, Serial No. 179,553

1 Claim. (Cl. 232—43.1)

1

This invention relates to a smoking stand, and more particularly, has reference to a smoking stand construction particularly adapted as part of a combination including an ash tray, smoking stand, cigarette container, and lighter.

By way of background, it may be noted that smoking stands as heretofore devised and commonly used sometimes include an ash tray having a normally closed opening, said opening adapted to be exposed for the purpose of causing the ashes to drop within a well disposed therebelow. However, in these devices as heretofore made, it is generally necessary to remove the top of the well, to take out of the well a special container in which said ashes are deposited, or alternatively, it is necessary to completely invert the stand for the purpose of emptying said well.

An important object of the present invention, accordingly, is to provide a generally improved construction for an article of this character, wherein, in all forms of the device, means are provided that normally close the opening in the ash receiver, and also an opening in the lower end of the well, said means being selectively operable in a manner to open the first-named opening to the exclusion of the second, and the second-named opening to the exclusion of the first, thus to permit the deposit of ashes from the receiver into the well whenever desired, and thus also to permit the emptying of the well whenever desired and without the inconveniences which have been noted with respect to constructions for devices of this type presently in general use.

Another important object is to provide a construction for a smoking stand or the like which can be embodied in a smoking stand of any design, whether it be a floor-type stand, wall-hung stand, or a table model.

Still another object is to provide a design for a smoking stand which will provide the beneficial results desired, and which will at the same time be particularly adapted for embodiment in an attractive design including such other accessories as a lighter, humidor or cigarette box, and ash tray.

Still another object is to provide a construction for a smoking stand or the like which will be capable of manufacture at relatively low cost considering the desirable benefits to be obtained.

With the foregoing and other objects in view which will appear as the description proceeds, the invention consists of certain novel details of construction and combinations of parts herein-after more fully described and pointed out in the

2

claim, it being understood that changes may be made in the construction and arrangement of parts without departing from the spirit of the invention as claimed.

5 Referring to the drawings:

Figure 1 is a side elevational view, portions being shown in vertical section, illustrating one form of the invention.

Fig. 2 is a top plan view.

10 Fig. 3 is a section on line 3—3 of Fig. 1.

Fig. 4 is a view similar to Fig. 1 and illustrating a modified construction.

Fig. 5 is a view similar to Fig. 1 and illustrating still another modified form.

15 Referring to the drawings in detail, in the present instance I have illustrated the invention as embodied in a floor-type smoking stand. However, this is illustrated purely as one preferred example of a type of stand to which the invention is readily adapted. It will be understood that the invention is equally well adapted for embodiment in table model stands, wall-hung stands, or any other type of smoking stand.

20 Additionally, and at the outset, it may be noted that I have illustrated in combination with the present smoking stand various accessories such as a cigarette and cigar holder or box, but again, it is believed worthy of note that this can of course be omitted since it plays no part in the 25 actual mechanical operation of the smoking stand, although in the commercial embodiment of the invention said stand would include these desirable accessories.

25 In the form of the invention illustrated in Figs. 1 to 3 inclusive, the floor-type stand there illustrated includes a base 1 rigid with the up-standing hollow body 2 here shown as cylindrical in cross sectional configuration. However, the cross sectional configuration of the body 2 can be varied as desired, without departure from 30 the spirit of the invention as claimed.

35 Mounted in the upper end of the body 2 is the concavo-convex ash receiver 3 having a large center opening 4 normally closed by a circular 40 concavo-convex valve member 5.

45 The valve member 5, which can be termed the upper valve member, is curved or bowed upwardly as distinguished from the receiver 3 which is depressed or dished downwardly.

50 Formed in the center of the valve member 5 is the opening 6 whereby said member 5 is slidably mounted upon a vertically disposed operating rod 7 extending upwardly through the center portion of the hollow body 2, and projecting upwardly through the receiver 3. The upper end

of the operating rod 7 is provided with a knob or operating handle 8, whereby a user can pull upwardly upon the rod or press downwardly thereupon, depending upon the use to which the rod is to be put.

Abutting at one end against the valve member 5, so as to press said valve member yieldably and upwardly into position to close the opening 4, is a coil spring 9, surrounding the rod 7, said spring abutting at its other end against a bearing collar 10 through which the rod 7 is slidably positioned, said bearing being integral or otherwise made rigid with diametrically opposed radial arms 11 the outer ends of which are formed with lateral extensions 12 riveted or otherwise rigidly secured to the wall of the hollow body 2.

The rod 7, immediately above the valve member 5, is rigid with an annular collar 9', this constituting a stop collar. It will thus be seen that whenever the rod is pressed downwardly, the collar 9' will engage the upper valve member 5, and force it downwardly against the action of the spring 9, to expose the opening 4, and thus cause any ashes which may have been deposited in the receiver 3 to gravitate into the well below the receiver, there to accumulate until such time as the well is to be emptied in a manner to be presently made apparent.

The lower end of the operating rod 7 is slidably in a center opening 13 formed in a concavo-convex lower valve member 14, said valve member 14 being bowed upwardly and being in peripheral engagement with the edge portion of a center opening 15 formed in the concavo-convex bottom plate 16 secured to the wall of the hollow body 2 and preferably elevated somewhat above the floor or other supporting surface.

The lower end of the rod 7 is provided with a stop collar 17, which is adapted to engage the lower valve member 14 whenever the rod 7 is pulled upwardly by a user, thus to elevate the valve member 14 in a manner to expose the opening 15 and thereby permit the well to be emptied of accumulated ashes.

It will thus be seen that by depression of the knob 8, the opening communicating between the receiver and the well is exposed while the opening at the lower end of the well still remains closed. Thus, ashes can be regularly emptied out of the receiver and can be permitted to accumulate in the well as necessary.

When, however, the well is to be emptied, it is necessary only that the user now pull upwardly upon the knob 8, and this upward movement of the rod 7 will cause the stop collar 17 to engage and elevate the lower valve member 14. Thus, the opening 4 will now be held closed while the opening 15 is opened for the purpose of emptying the well of accumulated ashes.

In the present embodiment of the invention, I prefer to provide for use with the smoking stand a combination cigarette box and lighter, and to this end, upwardly converging supports 18 are riveted or otherwise fixedly secured by fastening elements 19 to the upstanding annular flange 20 formed upon a surrounding wedge 21 that includes the depending annular lower flange 22 extending around the hollow body 2. Mounted upon the supports 18, and spaced above the ash receiver 3, is a cigarette or cigar humidor or container 23, which may be closed with a lid containing a cigarette lighter, not shown.

Referring to the form of the invention illustrated in Fig. 4, this form of the invention in-

cludes a depressed receiver 24 having a center opening 25 normally closed by the upper valve member 26 rigidly mounted upon an operating rod 27 having at its upper end the knob 28. A spring 29 surrounds the rod and abuts at one end against the upper valve member 26, and at the other end against a collar 30 on a spider 31 rigidly mounted within the well.

From the construction which has been so far described, it will be seen that the spring 29 serves to hold the valve member 26 normally pressed upwardly against the edge of the opening 25, so as to hold said opening normally closed.

However, upon depression of the knob 28, the opening 25 is exposed to permit ashes to be dropped from the receiver 24 into the well, there to accumulate until such time as the well is to be emptied.

The well is closed at its lower end by the downwardly dished bottom plate 32 having the center opening 33 closed by the lower valve member 34 that is slidably mounted upon the shaft 27. A spring 35 abuts at one end against the member 34 so as to yieldably force it upwardly into a position to hold the opening 33 normally closed. At its other end, the spring 35 abuts against a collar 36 rigid with a spider 37 mounted in the lower portion of the hollow body 2.

A collar 38 is rigidly mounted upon the shaft 27 or operating rod 27, substantially intermediate the opposite ends of said shaft, and is normally spaced a short distance above the lower valve member 34.

It will be seen that depression of the shaft 27 a short distance, will be sufficient to expose the opening 25 for the purpose of causing ashes to gravitate from the ash receiver into the well. However, this short downward travel will not bring the collar 38 into engagement with the lower valve member 34, and thus, even though the upper opening should be exposed, the lower opening will remain closed.

However, if the knob 28 is pressed downwardly still further, not only will the upper opening be opened, but also, the opening 33 at the lower end of the well will now be open, because the collar 38 will engage the lower valve member 34, and against the action of the spring 35 will depress said lower valve member so as to expose the opening 33, thus to cause ashes accumulated within the well to gravitate out of said lower opening to any suitable receiver over which the smoking stand may be temporarily positioned for this purpose.

In the form of the invention as illustrated in Fig. 5, in this modification the depress receiver 38 is provided with a center opening 39 normally closed by the upper valve member 40 positioned immediately thereabove and slidably mounted upon a rod 41 having rigidly mounted thereon a stop collar 41' disposed immediately below the upper valve member 40 and adapted to cause elevation of the upper valve member whenever the rod 41 is lifted.

In this form of the invention, the well is closed at its lower end by the bottom plate 42 having the center opening 43 normally closed by the lower valve member 44 engageable by a collar 45 rigid with the lower end portion of the rod 41, the lower valve member 44 being yieldably pressed upwardly against the collar 45 by means of a spring 46 the other end of which abuts against a spider or partially cut away bottom plate 41 rigidly mounted at the lower end of the hollow body 2 and extending thereacross, said member

47 having the centrally disposed nipple 48 through which the rod 41 is slidably positioned.

In use of the form of the invention illustrated in Fig. 5, the user pulls upwardly upon the rod 41 if it is desired to cause ashes that may have accumulated within the receiver 38 to fall into the well. Elevation of the member 40 is caused, of course, by engagement of the collar 41' with said member.

This operation will not cause opening of the bottom opening 43, the lower valve member 44 being slidably positioned upon the member 41 and not being engaged in any way by upward movement of said member 41. The spring 46, in other words, holds the lower member 44 yieldably in position to close the opening 43 at this time.

However, if it is desired to empty the well of ashes which may have accumulated therein, it is necessary only to press downwardly upon the knob at the upper end of the rod 41. By so doing, the user causes the collar 45 to engage the lower valve member 44 and force it downwardly with the rod against the action of the spring 46. This causes the lower opening 43 to be exposed, as a result of which ashes which accumulated within the well will gravitate downwardly into any suitable container or receiver, not shown.

In all forms of the invention, it will be understood that the construction is well adapted for use with a table model or wall-hung type of smoking stand. In such instances, the dimensions of the smoking stand, particularly the well portion, would probably be varied somewhat, and most usually said dimensions would be cut down as necessary. In any event, the plunger rod can in all instances be of any desired length, and the operation would be the same.

In this connection, it will be appreciated that all forms of the invention illustrated have in common certain important characteristics. In each form of the invention, the well is provided with openings at the upper and lower ends there-

of, and these openings are adapted to be selectively uncovered by manipulation of a single operating rod or plunger. Within the scope of the appending claim, it is this concept which I desire to protect.

What is claimed is:

In a smoker's stand a hollow body; a receiver extending across and closing the upper end of said body, said receiver having a center opening; a bottom plate extending across the lower end portion of said body, there being defined between said receiver and bottom plate a well for accumulated ashes, said bottom plate having a center opening; a plunger mounted for up and down sliding movement upon said body and extending through said well and openings; upper and lower valve members both slidably mounted upon said plunger and positioned to normally close the openings of the receiver and the bottom plate; spaced collars rigid with said plunger, one of said collars underlying the upper valve member and the other collar overlying the lower valve member, whereby on elevation of the plunger the upper valve member will be elevated to expose the opening of the receiver and whereby on depression of the plunger the lower valve member will be depressed to expose the opening of the bottom plate; and a spring underlying the lower valve member and normally biasing said lower valve member and plunger upwardly.
